UNITED STATES PATENT OFFICE.

JAMES MCADAM, OF POSTVILLE, IOWA.

BUTTER-TUB.

SPECIFICATION forming part of Letters Patent No. 357,935, dated February 15, 1887.

Application filed June 15, 1886. Serial No. 205,276. (No model.)

To all whom it may concern:

Be it known that I, JAMES MCADAM, a citizen of the United States, residing at Postville, in the county of Allamakee and State of Iowa, 5 have made certain new and useful Improvements in Butter-Tubs, of which the following is a specification.

In the drawings, Figure 1 is a perspective view of my butter-tub. Fig. 2 is a section 10 showing the parts, and Fig. 3 is a detail showing the way I rivet the retaining-tongues to the tub.

A is the butter-tub, B the lid or cover, C the channel or bend, D the packing, E the 15 flange, and F the retaining-tongue.

My present invention has relation to the kind of butter-tubs described in Letters Patent of the United States No. 309,969, issued to me December 30, 1884, and its principal object is to render the exclusion of air in such 20 butter-tub more perfect by a better attachment of the lid to the tub.

In making my improved butter-tub I take, preferably, a tub of the construction and general shape of the one described in my patent above referred to. To make the exclusion of air from the tub, which has a deteriorating effect on the butter contained therein, more perfect and secure, I employ a padding or 25 cushion of cotton, felt, cloth, or other suitable material interposed between the upper rim of the butter-tub and the lid. The top is provided with a free edge, which is bent into a groove or channel adapted to fit in use snugly 30 over the upper rim of the tub, as will be seen from a reference to the drawings. In the bottom of the bend or groove in the lid, formed by bending its edge up and over the top of the tub, as above, I place packing of any suitable 35 material, as above described. This packing rests upon the upper rim of the tub, and when the top is down in place it is compressed in the groove or channel in the top tightly against and around the upper rim of the tub, 40 forming an air-tight cushion or packing which will effectually exclude and prevent the admission of air. The free edge of the top is bent down a convenient distance after passing over the rim of the tub and turned out into a

rim or flange. This rim or flange, as will be 50 seen from a reference to the drawings, stands practically at right angles to the side of the tub. It is provided at intervals around the tub with slots or holes, through which tongues like those described in my other patent are to 55 be inserted. These tongues are preferably riveted to the tub with one rivet each, as shown in Figs. 2 and 3, so that they can be turned down out of the way when the lid is off and the tub not in use. When the tongues are 60 inserted in the slots they are preferably bent outward and downward, though they may be bent over the top of the lid, if desired, thus drawing the lid securely down in place, pressing the packing against the upper rim of 65 the tub, and holding and securing the lid in position until it is desired to be taken off to remove the contents of the tub. This is done by simply straightening the tongues, so that they will slip out of the slots as the lid 70 is raised.

By bringing the edge of the lid over the top of the tub and down and turning it out in a flange, as above described, the slots may be placed in such outwardly-extending flange instead of in the groove or channel at the top of the tub, as shown and described in my other patent. This enables me to place the packing or cushion in such groove or channel immediately on the upper rim of the tub, which I 80 cannot do satisfactorily and securely where the slots are made in such groove or channel, as in my other patent.

What I claim as new, and desire to secure by Letters Patent, is—

1. In a butter-tub, the combination, with a pail or tub provided with tongues, of a cover having its free edge bent into a groove or channel fitting over the rim of the tub, and then turned outward into a flange or projection provided with slots, through which the tongues pass in use, substantially as described.

2. In a butter-tub, the combination, with a pail or tub provided with tongues riveted thereto with one rivet, of a cover having its free edge bent into a groove or channel fitting over the rim of the tub, and then turned outward into a flange or projection provided with

slots, through which the tongues pass in use, substantially as described.

3. In a butter-tub, the combination, with a pail or tub provided with tongues, of a cover having its free edge bent into a groove or channel fitting over the rim of the tub, and then turned outward into a flange or projection provided with slots, through which the

tongues pass in use, and a packing interposed in the groove or channel between the rim and the cover, substantially as described.

JAMES McADAM.
